FEED-WATER HEATER

Bartley R. McBath, Verona, N. J., assignor to
Worthington Pump and Machinery Corpora-
tion, Harrison, N. J., a corporation of Dela-
ware

Application February 24, 1939, Serial No. 258,134

3 Claims. (Cl. 122—438)

This invention relates to feed-water heaters, and more particularly to a secondary feed-water heater of the vapor and water contact type wherein the incoming water to a boiler is sprayed through the steam mass in the upper portion of the boiler for heating the water to steam temperature, thereby heating the incoming water to the temperature of the water in the boiler, thus preventing injury to the boiler from uneven temperature strains.

An object of the present invention is to provide a secondary feed-water heater of the type referred to which embodies means to protect the saturated-steam pipe in the boiler from the incoming water, means for deaerating the incoming water, and means whereby the steam utilized for carrying off the released gases is employed for useful work such as operating the pump which supplies the cold water to the system.

With these and other objects in view, as may appear from the accompanying specification, the invention consists of various features of construction and combination of parts, which will be first described in connection with the accompanying drawing, which shows a secondary feed-water heater constructed in accordance with this invention, partly in section and showing the cooperating units or elements diagrammatically, and the features forming the invention will be specifically pointed out in the claims.

Referring more particularly to the drawing, 1 indicates a steam boiler of locomotive or any approved type having the flues or tubes 2 therein through which the hot gases pass for heating the water indicated at 3, in the boiler.

The water is delivered to the boiler at some point along its length at its top or upper-most portion, either by means of an injector or from a regular feed-water heater or from both, and the present invention maintains this same arrangement of entry of the water into the boiler but it provides means and a construction for heating the incoming water substantially to the temperature of the steam.

In the present invention the boiler is illustrated as provided with deliveries of water both from an injector 5 of any approved construction and from a feed-water heater 6, also, of any approved construction. These delivery structures 5 and 6 deliver the water to the check valve structure 7. In the drawing the check valve structure 7 comprises the valve 8, which is positioned in the line 26 from the injector, and the valve 9, which is positioned in the line 10 from the feed-water

heater. The water from the injector 5 and feed-water heater 6 passes through the respective valves 8 and 9 into chambers 11, which merge and deliver the water through the delivery pipe 12 into the boiler 1. A spray head 14 is positioned at the outlet of the delivery pipe 12 to the boiler, and this spray head breaks up the incoming water into thin or small streams.

A shroud 15 is attached to the inner surface of the shell 4 of the boiler 1 at the top thereof and surrounds the spray member 14, serving the dual purpose of protecting the saturated-steam pipe 16, which leads the steam from the steam dome to the super-heater (both not shown) and of directing the water into the boiler. The shroud 15 has its inner or lower end shaped to form a substantially concave protecting portion 17 for the pipe 16, and this end, together with the main body of the shroud 15, directs the incoming streams of water in a cone-like spray into the boiler. The inner end of the shroud 15 outwardly of the closed portion 17 is open not only to let the water into the boiler but also to let steam from the upper part of the boiler pass into the shroud for the purpose of heating the fine streams of water, bring it up to the temperature of the steam, thus avoiding any strains or injury to the boiler because of uneven temperature strains and also raising the temperature of the water so that it may be more easily and readily converted into steam. The sides of the shroud 15 are also provided with openings 18 near the top of the shroud to permit steam from the top portion of the boiler to enter the shroud upwardly of the water outlets and countercurrent or crosscurrent to the direction of travel of the water for further facilitating the heating of the water, and also to permit deaeration of the incoming water. The gases released from the incoming water through the deaeration action, together with a certain amount of steam or vapor pass into the chamber 20 at the top of the shroud 15 or at the top of the secondary heater. The chamber 20 is formed by a partition 21. A vent or outlet pipe 22 opens into the top of the chamber 20 and serves to carry off the released gases and the steam which pass out of the secondary heater with such released gases.

The present invention embodies the utilization of this steam, resulting in economy of steam and consequent fuel savings. The steam which passes through the vent pipe 22 may be led to the cold water pump 23 of the feed-water heater 6 for operating this pump, or any other steam operated accessory of the locomotive.

- The cold water from the tender (not shown) is picked up by the cold water pump 24 and passes through the feed-water heater 6, and is pumped by the hot water pump 23 through the boiler 5 check valve 9, and the secondary feed-water heater structure, into the boiler, or if the injector 5 is used, incoming water is pumped from the tender (not shown) through the inlet 25 of the injector 5 and outwardly through the pipe 26 to the boiler 10 check valve 8 and thence through the secondary heater into the boiler.

While in the drawing and the above description the steam which passes through the vent pipe 22 is used to operate either of the pumps 23 or 24, 15 it is to be understood that it may be used to operate any steam operated accessories of the boiler or locomotive such as the head light turbine, etc.

It will be understood that the invention is not to be limited to the specific construction or arrangement of parts shown, but that they may 20 be widely modified within the invention defined by the claims.

What is claimed is:

1. In a feed-water heater, the combination 25 with a boiler having a saturated-steam pipe therein, of an inlet for water at the top of said boiler, a shroud within the boiler for receiving incoming water from said inlet and having its inner end open to receive steam from the boiler 30 and permit passage of water into the boiler, and means at said inlet to spray the incoming water through said shroud and directly into the boiler in small, thin uninterrupted streams, the passage of steam in said shroud being countercurrent to 35 the passage of water therein, said shroud having an outlet therein for the outlet of a limited amount of steam together with the gases released from solution by the deaerating effect of the counter-flowing steam, said shroud shaped to 40 form a protecting cover for a part of said saturated-steam pipe to prevent contact of incoming water with the pipe.

2. In a feed-water heater, the combination with

a boiler, of an inlet for water at the top of the boiler, a shroud within the boiler for receiving incoming water from said inlet and having its inner end open to receive steam from the boiler and permit passage of water into the boiler, and means at said inlet to spray the incoming water through said shroud and directly into the boiler for contact with the surface of the water in the boiler in small, thin broken-up streams, the passage of steam in said shroud being opposed to the 10 passage of water therein, said shroud having an outlet therein at its highest point for the outlet of a limited amount of steam together with the gases released from solution by the deaeration 15 effect of the opposed flowing steam, said shroud having a partition extending thereto near its highest point and forming a collection chamber open to the interior of the shroud and to said outlet.

3. In a feed-water heater, the combination 20 with a boiler having a saturated-steam pipe therein, of an inlet for water at the top of said boiler, a shroud within the boiler for receiving incoming water from said inlet and having its inner end open to receive steam from the boiler and permit passage of water into the boiler, and means at said inlet to spray the incoming water through said shroud and directly into the boiler for contact with the surface of the water in the boiler in small, thin streams, the passage of 30 steam in said shroud being countercurrent to the passage of water therein, said shroud having an outlet therein for the outlet of a limited amount of steam together with the gases released from solution by the deaerating effect of the counter-flowing steam, said shroud shaped to form a protecting cover for a part of said saturated-steam pipe to prevent contact of incoming water with the pipe, said shroud provided with openings 35 therein near its upper-most portion for the inlet 40 of steam.

BARTLEY R. McBATH.
